Primary Examiner — Janice Hallmark*(74) Attorney, Agent, or Firm* — Berenato & White, LLC(57) **CLAIM**

The ornamental design for a lite for doors and entryways, as shown and described.

DESCRIPTION

FIG. 1 is a front elevational view of a lite for doors and entryways showing my new design;

FIG. 2 is a front perspective view thereof;

FIG. 3 is a front elevational view of a second embodiment of a lite for doors and entryways; and,

FIG. 4 is a front perspective view thereof.

The rear elevational view of each of FIGS. 1 and 3 is a mirror image thereof.

1 Claim, 4 Drawing Sheets(56)
